UNITED STATES PATENT OFFICE.

EDWARD F. PARKS, OF PROVIDENCE, AND JOHAN A. ANDERSON, OF CRANSTON, RHODE ISLAND, ASSIGNEES, BY MESNE ASSIGNMENTS, TO UNIVERSAL WINDING COMPANY, OF BOSTON, MASSACHUSETTS, A CORPORATION OF MASSACHUSETTS.

HAND-KNOTTER.

1,263,101.

Specification of Letters Patent. Patented Apr. 16, 1918.

Application filed November 4, 1915. Serial No. 59,663.

To all whom it may concern:

Be it known that we, EDWARD F. PARKS and JOHAN A. ANDERSON, citizens of the United States, residing at Providence and Cranston, respectively, in the county of Providence, State of Rhode Island, have invented certain new and useful Improvements in Hand-Knotters, of which the following is a specification.

10 Our invention relates to improvements in hand, knot-tying devices for tying together the ends of a thread or yarn. The object of our improvement is to provide a self-acting knotter which may be held conveniently on the fingers of the hand without strapping it thereto, and in such manner that it may be thrown out of operative position, while still retained on the fingers, so as not to interfere with the use of the hand for other purposes than that of tying the knot.

In general our improved knotter is of the same type as that shown in United States Patent No. 1,041,163, granted to William Renfrew, Oct. 15, 1912. The present improvement consists particularly in adapting the device to be more conveniently held on the hand without the employment of straps, buckles or other fastening-means while providing for shifting the knotter to hold it out of the way so as not to obstruct the use of the hand for other purposes; in rendering it more convenient and easy to operate in tying the knot; in providing a protecting case for the operating parts of the device to prevent the insinuation of dirt and lint; in rendering it more positive and efficient in action; and in generally simplifying the structure and arrangement of its mechanism.

15 The manner and means for carrying out our improvement are fully described in the following specification, illustrated by the accompanying drawings, in which like reference characters designate like parts. In the drawings:

Figure 1 is a side elevation of our improved knotter showing the manner in which it is held on the fingers of one hand while the other hand manipulates the thread 20 to tie the knot;

Fig. 2, an enlarged plan view of the device illustrating the manner in which the

operating-mechanism is inclosed in its protecting case;

Fig. 3, an enlarged sectional view of the device taken on the axis of the pivot looper-arm and illustrating the controlling-means for the latter;

Fig. 4, an enlarged view in perspective of the thread-cutter or end-severing knife;

Figs. 5, 6, 7 and 8, enlarged detail views of the looper-mechanism of the device illustrating the several steps in the operation of tying the knot and severing the ends of the thread;

Fig. 9, an enlarged side view showing the method of adjusting the end-severing knife;

Fig. 10, an enlarged side view of the mechanism of a modified form of the device;

Fig. 11, a sectional view of the same taken 70 on the line 2—2 of Fig. 10;

Fig. 12, a view similar to Fig. 10, showing still another modification of the invention;

Fig. 13, a sectional view of this embodiment taken on the line 3—3 of Fig. 12; and

Fig. 14, a detail view in perspective of the thread-gripper spring-clamp;

In the device of the Renfrew patent above referred to the operating-mechanism of the knotter consists essentially of a swinging looper-arm pivoted on a main holding-frame and having opposite jaws adapted to grip the ends of the thread looped around the end of the arm to draw them through the loop to tie the knot. Secured to the frame is a knife arranged in the path of the looper as it swings about its pivot to adapt it to sever the ends of the threads as the knot is tied and drawn up taut. In the Renfrew device the holding-frame is provided with a strap and buckle arrangement for fastening it to the palm of the hand and means are also provided on the frame for guiding and holding the threads in place while the latter are being tied together. In our present improvement we employ these same essential elements of the pivoted looper, cutting-knife and thread-holding means, but arrange them in more convenient position while also simplifying their construction and inclosing the operating parts within a casing which protects them from lint and dust and prevents the threads from catching on projections or other parts. In addition

100

we dispense with the holding-strap and buckle and adapt the device to be held on the fingers so that it may be shifted around out of the way when the operator wishes to have his hand free for other work. To provide for these improvements the device is constructed as follows:

Referring first to Fig. 1, the main frame or holding-means for the knotter comprises a small circular casing C, similar in shape to a watch-case or locket, with a loop-like handle or finger-receiving means D extending downwardly from its side. The casing C is preferably constructed from sheet-metal struck up with a main saucer-like portion c, see Fig. 3, to the rim of which is fitted a convexly-shaped cover c'. An axial bolt or pin B extends through the two parts c and c' and is threaded at its ends to receive suitable fastening-nuts b, b', which are set up against the side walls of the casing to hold the sections together in fixed relation. The finger-hold D is also preferably constructed from sheet-metal with a main strap-like portion bent in the form of a double loop d, d'. One portion d of the finger-hold D is made in the form of a complete circle having its end reaching around in a reverse curve to form the hook-like portion or open loop d'. Formed integral with the loop d is an arm d² bent upwardly at substantially right-angles and shaped to conform to the outer convex face of the main casing-section c. The arm d² is provided with an opening d³ adapted to receive the axial bolt B and the outer nut b' on this end of the bolt serves to secure the arm in place against the side of the casing C as illustrated in Fig. 3. The arm d² has an angular extension d⁴, see dotted lines in Fig. 1, which lies alongside the curved, outer face of the casing C, as shown more particularly in Fig. 2, and projects outwardly in a horizontal direction beyond the rim of the section c. A screw e, see Fig. 2, reaches through the section c and the extension d⁴ with a nut e' at its end acting to draw the parts together to more securely fasten the part D to the casing C.

Referring again to Fig. 1, the cover portion c' of the casing C is formed with a fin-like extension F having its outer, divergent, curved edge f of a greater radius than that of the periphery of the casing, but merging tangentially therewith at its top. At the bottom the eccentric fin F is formed with a finger f' bent rearwardly at right-angles to its main portion, or in a plane parallel with the axis of the casing C. Secured to the projecting end d⁴ of the member D, by means of a screw e⁵, is a guide-member and thread-holding element G constructed of sheet-metal bent in channel form, or substantially U-shape in cross-section, as shown in Fig. 2. One side of the

guide-member G is arranged in the plane of the fin F and is formed with an extension g reaching downwardly to aline its curved edge closely adjacent the edge of the fin, see Fig. 1. In this manner the parallel edges of the guide G and fin F form a contracted opening or slot s adapted to receive the ends of the thread as they are manipulated to tie the knot in the manner and for the purpose as more fully explained herein-after. At its bottom the extension g is formed with a finger g' which projects across and overlies the top of the bent finger f', the purpose of this arrangement being to locate the guide G with relation to the edge of the fin F when securing it in place with the fastening-screw e⁵. The outer, flat portion of the guide G, which forms the bottom of its U-shaped channel, lies in a plane parallel with the axis of the casing C, and at its top are two divergent, curved prongs or horns g², g² which form a substantially V-shaped thread-receiving passage or guide v between them. At the bottom of the guide G is a single, curved prong g³ formed with a crescent-shaped edge g⁴, see Fig. 2, across which the thread is drawn as it is led up between the prongs g², g². Between the upper and lower prongs g², g² and g³ the outer face of the flat portion of the guide G is scored with a series of cross cuts or serrations which provide the downwardly-pointed teeth g⁵, see Fig. 1. As the thread is drawn up across the prong g³ and between the prongs g², g² it is pressed against this serrated face of the guide G by the operator's thumb to anchor the free ends and hold them fast during the tying of the knot as later explained.

Within the channel-like opening of the guard G is arranged the knife or thread-cutter K which acts to sever the ends of the thread while the knot is being tied. As shown in detail in Fig. 4, the knife K is constructed of sheet-metal bent in right-angular form and provided with an inwardly-curved blade k which is sharpened along its upper edge. One wing k' of the knife is provided with a slot k² adapted to receive the holding-screw e⁶ for the guide G when the knife is arranged in position between the side of the guide and its supporting arm d⁴, see Fig. 2. In this manner the knife K is clamped securely in place with its cutting-blade positioned slightly above the thread-receiving slot v of the guide G and curved back away from the serrated face of the thread-holding portion thereof, see Fig. 5. The slot k² in the knife K allows for a slight up and down adjustment of the cutting blade k to regulate its position in relation to the thread-guiding opening v, and the knife and its associated guide G may also be rocked about the axis of the screw e⁶ to adjust the position of the cutter-

blade in relation to the end of the looper-arm L as shown in Fig. 9. The looper L is pivotally mounted on the axial bolt or pin B which extends through the sides of the casing C and the mechanism for controlling its operation is inclosed within the casing and arranged as next described:

Referring to Fig. 3, a sleeve or bushing H is mounted free to rotate on the bolt or pin B and is held from side play by the nuts b, b against which its ends abut. Mounted fast on the sleeve H is the channeled arm L, constructed of relatively thin sheet-metal bent to a U-shaped cross-section with parallel sides l, l, and arranged with its outer end projecting through an opening c³ in the peripheral rim of the casing C. The rim opening c³ extends substantially half way around the circumference of the casing C, as shown most clearly in Figs. 5 to 8, to allow the arm L to swing through an arc of approximately one-hundred-and-eighty degrees. Secured to the arm L is a cylindrical guard or ring R surrounding the interior of the casing C in close proximity to the inner walls of its rim. The arm L projects through an aperture r in the guard-ring R and its sides are soldered or otherwise attached thereto to secure the two parts together so that they rotate about the axis of the bolt B as one element. The purpose of the ring R is to serve as a closure for the opening c³ in the rim of the casing C, it being noticed from Fig. 3 that the sides of the ring overlap the edges of the opening, so as to prevent dust, lint or particles of thread from being admitted to the interior of the knotted. 40

Mounted free to slide longitudinally of the sleeve H and inclosed within the sides l, l of the arm L are two thread-grippers or jaw-members J, J. The grippers J, J are secured rotatively with the arm L by means 45 of a cross-pin l' fastened in the sides l, l and extending through a hole j in the grippers. The hole j is large enough to provide a liberal clearance for the pin l' so that the grippers cannot bind thereon but 50 will have a free movement in sliding laterally toward and away from each other. The outer ends of the grippers J, J project beyond the end of the arm L and are squared off to provide a parallel sided nose j', see 55 Fig. 5, around which the threads are drawn into the knot as later explained. Where the adjacent sides of the two grippers meet at their ends they are rounded inwardly as illustrated in Fig. 3, to provide a flaring 60 mouth m for the entrance of the thread between their jaws. At the opposite or butt end of the grippers J, J is a spring-clamp or tension-member T shown in detail in Fig. 14. This consists simply of a section 65 of spring-metal bent in substantially U-

shape to adapt its legs t, t to straddle the sides of the two grippers J, J, see Figs 3 and 5. The purpose of the spring-clamp T is to hold the two grippers normally sprung together with their adjacent sides in contact while allowing the outer jaw-ends of the grippers to be spread apart slightly when the thread is drawn into the mouth m. In this way the ends of the thread may be drawn into place to be seized by the 70 jaws of the gripper to hold them taut while the knot is being tied as later explained. It will be noted from the dotted lines in Fig. 3 that the end of the arm L is cut away in a clearance-slot l² adapted to receive the ends of the thread as they enter between the jaws of the grippers, although this is not essential.

Coiled around the sleeve H at the side of the arm L is a spring O having one of its 85 ends anchored in a hole in a pin or projection o on the interior of the casing C. The opposite end o' of the spring O extends up alongside the arm L with its extremity bent at right-angles and inserted through a 90 hole l³ in the arm L and the two grippers J, J. The spring O tends to resist the rocking movement of the arm L in the direction indicated by the arrow a, Figs. 5 to 9, and serves to return the arm to its 95 initial position bearing against the end of the opening c³ of the casing C as shown in Fig. 2. The method of operation of this form of embodiment of our invention is as follows:

The knotted is usually held in the left hand with the fingers inserted through the loops of the member D and the thumb pressed against the toothed face of the guide G. Most operators prefer to hold the device as illustrated in Fig. 1 with the end of the first finger reaching through the loop d and the second finger crooked around the open loop d'. When used in this manner the thumb may be removed from the guide 100 G and the whole knotted swung around on the index finger to bring it down against the back of the hand. That is to say, the knotted can be tilted back around the operator's first finger, from which it remains 105 suspended out of the way so that all the fingers are left free and the palm of the hand unobstructed. In some instances the operator prefers to hold the knotted with the loop d on the second finger, in which 110 case the device may be shifted down into the palm of the hand to leave the thumb and first finger entirely free and unhampered for other work. With either method of holding the device it is a simple matter 115 to bring it into operative position or to shift it out of the way so as to leave the hand free to perform other duties besides that of tying the threads together.

With the knotted held in the left hand in 120

the position illustrated in Fig. 1, the operator grasps the threads x , x' to be tied together in the right hand while their severed ends are held under the fingers of the left hand. The right hand is then used to draw the threads up across the guiding face g^4 of the prong g^3 to insert them under the end of the thumb pressing against the guide G. That is to say, the free ends of the thread 10 are drawn in under the thumb and pressed against the serrated face of the guide G to be held fast while their leading ends are passed up through the guiding-passage w between the prongs g^2 , g^3 . From the groove 15 v of the guide G the threads x , x' are drawn across to the looper L and looped around the sides of the latter from the front to the rear and then out to the front again to cross them over the portion drawing forward 20 from the guide. In this way the threads form a complete loop or bight x^2 crossing each other at the left of the arm L. The right hand is then carried downward past the front of the casing C to draw the threads 25 down through the curved guiding-passage s in back of the fin F to direct them around the rim of the casing. As the threads are pulled down in this manner the loop x^2 will tighten around the end of the arm L and the 30 latter will be rocked toward the guide G in the direction indicated by the arrow a , Fig. 5. Figs. 5 to 8 illustrate the various steps in the operation of the looper L during the 35 tying of the knot and for the sake of clearness in these views the casing C is shown with its cover removed and the guide G illustrated in section taken on a median, vertical plane. It will be noted from Fig. 5 that as the arm L swings down in the direction indicated by the arrow a , the ends of the 40 grippers J, J approach the blade k of the knife K with the threads x , x' drawing across the cutting edge of the blade. Now, as the ends of the grippers swing down past the blade 45 k, the free ends of the threads are held taut by the thumb pressing against the guide G and hence the length of threads extending between the guide G and the arm L will be drawn up between the jaws of the grippers 50 as shown in Fig. 6. In other words, the tension on the threads consequent to their ends being anchored under the operator's left thumb while being pulled down by the right hand will cause them to be drawn into the 55 mouth m of the grippers J, J to insert them between the jaws of the latter to be seized thereby. It is to be understood that while in the drawings the threads are represented as being rather loose where they encircle the 60 looper, as a matter of fact they draw up tight, it being impossible to show them in such manner without confusion of the lines of the drawing. Likewise, in Fig. 1 the right hand is shown in position at some distance below the knotter so as not to obscure 65

the other hand, while in practice the hand would naturally grasp the threads quite close up to the loop.

As the loop tightens around the arm L and the threads are drawn down against the 70 blade k of the knife K, see Fig. 6, the length extending beyond the grippers J, J to the guide G will finally be severed as shown in Fig. 7. At this point the loop x^2 will slide off from the end of the arm L onto the projecting nose j' of the grippers J, J. Meanwhile, the arm L continues to swing downwardly under the pull on the threads exerted by the right hand and eventually the loop will slide off from the ends of the grippers. As the loop x^2 slides off from the nose j' it passes over the severed ends of the threads which are held fast between the jaws of the grippers by the action of the clamp T, and the knot is then formed as shown in 80 Fig. 8. Finally, as the arm L reaches the limit of its movement and brings up against the end of the opening c^3 in the casing C, see Fig. 8, the pull on the threads will cause the knot to be drawn up tight and its ends to be released from the jaws of the gripper, thus resulting in the splicing of the threads with their ends severed at a short distance from the knot. As soon as the ends of the threads x , x' have been pulled free from the 85 jaws of the grippers J, J the spring O acts to return the looper L to its initial position as shown in Fig. 1, ready for the next operation of tying another knot. By adjusting the knife K up and down on the guide G its 90 cutting operation can be properly timed in accordance with the movement of the looper L, and by varying the position of the knife with respect to the ends of the grippers J, J the length of the severed ends may be 95 regulated as required.

Figs. 10 and 11 illustrate another embodiment of the invention in which the construction of the operating-mechanism is slightly modified. As shown in Fig. 11 the casing G 110 has its two sections c and c' sprung together with a dove-tailed joint surrounding the rim. Axially arranged within the casing are opposite hardened bearing-studs p , p' formed with tapered sockets for receiving the pointed ends of a rotatable spindle P. Preferably, one of the studs p is adjustable in the side of the casing to provide for setting it to allow for a free bearing support for the spindle P and the outer nut b' serves 115 as a check to lock it in its adjusted position. Mounted fast on the spindle P is an arm U 120 formed with an elongated hub u carrying a flange u' secured at its end. A second arm U' formed with a hub u' is mounted on the 125 hub u of the member U and held in place by the flange u'. The bore u² in the hub u' is tapered outwardly to allow the arm U' to rock toward and away from the arm U, and a pin u⁴ secured in the arm U extends 130

through a hole u^5 in the arm U' to adapt the two arms to rotate together about the axis of the spindle P . A wire spring Y is coiled around the periphery of the hub u^2 of the arm U' with one end anchored in the pin q extending from the side of the casing C , while its opposite end is inserted in a hole y' in the arm U' . The spring Y tends to normally rock the arm U' laterally against the arm U and also acts to swing both arms back into their initial position, as shown in Fig. 10, after they have been carried down past the guide G to complete a knot. During the first part of the turning movement of the arms U, U' about their pivot they are held slightly apart, as illustrated in Fig. 11, by means of a wedge-member of dagger W . Referring to Fig. 10, the dagger W is preferably formed from an extension of the rim 20 of the casing C bent inwardly and twisted around at right-angles to bring it into position in the path of the arms U, U' as they swing back toward the top of the casing. The outer rounded end of the dagger W is 25 pointed or tapered, as shown at w , Fig. 11, to adapt it to force an entrance between the adjacent sides of the arms U, U' as the latter move back under the action of the spring Y . The method of operation of this arrangement of mechanism is as follows:

The bight of thread is formed around the ends of the two arms U, U' , which act conjointly as the looper, and as the arms are drawn downwardly toward the knife K they are held slightly apart by the action of the dagger W inserted between them. As soon, however, as the ends of the threads have been drawn up between the jaws of the two arms U, U' the latter will ride off from the end of the dagger W and will then be sprung together through the action of the spring Y . This causes the jaws to seize the threads to draw them through the loop as the latter slides off from the ends of the arms, the knot being formed and drawn taut in exactly the same manner as before described. As the arms U, U' are returned to their initial position by the spring Y the dagger W again acts to spread them apart so that they will be positioned to seize the ends of the threads again during the next operation of forming a knot. It will be observed that in the arrangement of the mechanism first described the looper-arm L which incloses the grippers J, J receives the loop of threads during the first part of their movement and holds it until the ends have been drawn up between the jaws of the grippers. This provides against the loop being tightened around the grippers to prevent them from opening up to receive the ends of the threads to be carried through the loop and in the arrangement of the mechanism last described the dagger W performs this same function.

65 In the embodiment illustrated in Figs. 12

and 13 we also dispense with an extra looper-member by forming the loop-guard or inclosing means for the grippers as an integral part of one of them. Referring to Fig. 13 the right-hand gripper-arm J is secured 70 fast to the sleeve H and is formed with a folded side J^2 spaced a slight distance apart from the main arm. Between the side J^2 and the arm J is the opposite gripper J' mounted free to slide laterally on the sleeve 75 H but held rotatively by the pin l' extending through both arms. The method of operation of this form of the device is substantially the same as that of the embodiment first described. The loop or bight in the 80 threads is formed around the arm J and its parallel, folded side J^2 and the gripper J' is free to rock between these two parts to allow the jaws to open to receive the ends of the threads to be drawn through the loop. 85

It will be seen that our improvement provides an extremely simple and efficient self-acting knotter of small compass and light weight. It may be held on the fingers of the hand without strapping it thereto in 90 convenient position for tying the knot and without obstructing the use of the hand for other purposes. Its operating parts are completely inclosed in a casing to keep them free from lint, dust and loose threads, thus 95 preventing interference with their action and providing for longer wear. The form of the casing provides for more convenient manipulation of the threads in tying the knot and guards against the possibility of 100 their catching on projecting parts or being obstructed to tangle and snarl the ends. The parts of the device being constructed from sheet-metal may be made relatively light without sacrificing strength and stiffness while also assuring more economical manufacture. 105

Various modifications other than those here shown might be made in the form and construction of the parts of the device without departing from the spirit or scope of the invention; therefore, without limiting ourselves to the exact embodiments herein illustrated and described, what we claim is:—

1. In a hand knitter, the combination 115 with a casing, of a swinging looper-arm pivoted within the casing and provided at its end with gripping-jaws projecting therefrom, a loop-like handle projecting from one side of the casing to adapt the knitter to be 120 held on the fingers of the hand, and a fixed thread-positioning member projecting from the opposite side of the casing in spaced relation thereto and arranged in position to adapt the threads to be held thereagainst by 125 the operator's thumb during the operation of looping them around the looper in the manner and for the purpose described.

2. In a hand knitter, the combination 130 with a casing, of a swinging looper-arm piv-

- oted within the casing and having gripping-jaws at its end projecting therefrom, of a handle projecting from one side of the casing, and a thread-positioning member projecting from the opposite side of the casing in spaced relation thereto and provided with an upright portion against which the threads are adapted to be held by the operator's thumb during their manipulation in 5
- 10 looping them around the looper, said thread-positioning member also having divergent branches for guiding the threads into place against its face.
3. In a hand knitter, the combination with a circular casing, of a swinging looper-arm pivoted concentrically within the casing and provided with gripping-jaws at its end projecting through the periphery thereof, and a member mounted on the casing in 15
- 20 spaced relation to its periphery and provided with guiding-means for positioning the threads to be tied, said member formed with a serrated face against which the ends of the threads are adapted to be held by the pressure of the operator's thumb.
4. In a knitter, the combination with a casing, of a swinging looper-arm pivoted within the casing and provided with gripping-jaws at its end projecting therefrom, 25
- 30 a handle projecting from one side of the casing and formed with loops for the insertion of the fingers therethrough, and thread-positioning means projecting from the opposite side of the casing in spaced relation thereto to adapt the threads to be held thereagainst by the pressure of the thumb during the operation of the looper in forming the loop.
5. In a hand knitter, the combination with a watch-like casing, of a looper pivoted within the casing and provided with gripping-jaws adapted to be oscillated about its rim, means for positioning the threads to be tied in relation to the looper, a curved guard 35
- 40 projecting from the rim of the casing downwardly beyond the thread-positioning-means for guiding the threads in drawing them down from the looper, and means for holding the knitter on the fingers of the hand.
6. In a hand knitter, the combination with a watch-like casing, of a swinging looper-arm pivoted within the casing and provided with gripping-jaws at its end projecting through an opening in the rim of the 45
- 50 casing, a thread-positioning member on the casing against which the threads are adapted to be held by the operator's thumb, and a knife mounted on the back of the thread-positioning means in spaced relation with the casing and arranged in the plane of movement of the looper to coöperate therewith as the latter swings about its pivot.
7. In a hand knitter, the combination with a watch-like casing, of a looper-arm 55
- 60 pivoted within the casing and provided with gripping-jaws at its end projecting through an aperture in the rim of the casing, a thread-guide mounted on the casing in spaced relation to its rim to adapt the threads to be held thereagainst by the operator's thumb, and a knife arranged between the thread-guide and the casing in spaced relation with the latter with its cutting edge extending across the plane of movement of the looper to adapt it to coöperate therewith.
8. In a knitter, the combination with a holding-frame having a handle formed with loops for the insertion of the fingers therethrough, of a pivoted looper-arm provided with gripping-jaws at its end for seizing the ends of the threads to be tied, fixed thread-positioning means against which the threads are adapted to be held by the operator's hand in alinement with the looper, 70
- 75 and a thread-guide formed with a curved guiding throat for directing the threads downwardly to cause the looper to swing about its pivot to seize the ends and draw them through the loop.
9. In a knitter, the combination with a pivoted looper-arm having gripping-jaws at its end, of a fixed guiding-member for positioning and holding the ends of the threads in alinement with the looper, means having a contracted curved guideway extending below the thread-positioning means for directing the threads downwardly as they draw around the looper to rock the latter on its pivot to cause it to seize the ends and draw them through the loop, and means for holding the knitter on the hand.
10. In a knitter, the combination with a pivoted looper-arm having gripping-jaws at its end, of a guiding-member for positioning and holding the ends of the threads in alinement with the looper, and means formed with a contracted guiding-slot extending downwardly from the thread-positioning means for directing the threads 80

severing knife arranged between the thread-guide and the pivot of the looper, and means to adjust the position of the knife toward and away from the looper and in angular relation thereto in relation to the thread-guide.

13. In a knotted, the combination with a pivoted looper having gripping-jaws at its end, of a thread-guide for positioning and holding the threads under the operator's thumb in alignment with the looper, an end-severing knife arranged between the thread-guide and the pivot of the looper, and means to adjust the knife up and down in the plane of movement of the looper and laterally in relation to the end of the looper.

14. In a knotted, the combination with a circular casing, of a looper pivoted within the casing and having gripping-jaws at its end projecting therefrom, a thread-guide mounted on the casing in spaced relation to its rim to adapt the threads to be held thereagainst by the operator's thumb, and an end-severing knife mounted on the thread-guide to adapt it to be adjusted longitudinally with respect to the plane of movement of the looper and laterally in relation to its end.

15. In a knotted, the combination with a cylindrical casing having an aperture in its rim, of a looper pivoted in the casing with its end projecting through the aperture, and a guard-ring secured to the looper to rotate therewith and arranged adjacent the rim of the casing with its edges overlapping the aperture to adapt it to act as an oscillating closure therefor.

16. In a knotted, the combination with a cylindrical casing having an aperture in its rim, of an oscillating looper-arm formed of U-shaped cross-section pivoted within the casing with its end projecting therefrom, parallel gripping-jaws arranged within the

sides of the looper-arm to adapt their ends to be sprung apart to seize the threads, and a guard-ring secured to the looper-arm to oscillate therewith and encircling the rim of the casing to overlap its aperture to serve as a closure therefor.

17. In a knotted, the combination with a two-part cylindrical casing, of an axial bolt extending between the sides of the casing to secure its parts together, a looper pivoted on said bolt with its end projecting through the rim of the casing to oscillate thereabout, and gripping-jaws on the looper for seizing the ends of the thread to draw them through a loop formed around the looper.

18. In a knotted, the combination with a two-part casing, of a bolt extending through the casing to secure its parts together, a sleeve rotatable on the bolt, a looper-arm fast on the sleeve, spring-pressed gripping-jaws at the end of the looper, and a spring for returning the looper to its initial position after it has been oscillated about its axis to form the knot.

19. In a knotted, the combination with a two-part casing, of a bolt extending through the casing to secure its parts together, a sleeve rotatable on the bolt, a looper-arm of U-shaped cross-section secured to the sleeve, parallel grippers slidable on the sleeve between the sides of the looper-arm and arranged with their jaws projecting from the end thereof, and resilient-means to hold the grippers normally sprung together while allowing their jaws to be spread apart to seize the thread.

In testimony whereof we affix our signatures in presence of two witnesses.

EDWARD F. PARKS.
